The ornamental design for a basket for a speaker, as shown and described.

DESCRIPTION

FIG. 1 is a bottom plan view of a basket for an audio speaker showing our new design;

FIG. 2 is a side elevational view thereof, the opposite side being a mirror image;

FIG. 3 is a bottom and right side perspective view thereof; FIG. 4 is a top perspective view thereof; and,

FIG. 5 is a top plan view thereof.

The broken line showing of the speaker cone and mounting ring on FIGS. 1-4 is for illustrative purposes only and forms no part of the claimed design.
